CLAIM

I claim the ornamental design for a tire, as shown and described.

DESCRIPTION

FIG. 1 is a perspective view of a tire showing my new design;

FIG. 2 is a front view of the tire as shown in FIG. 1, it being understood that the tread pattern repeats uniformly throughout the outer circumference of the tire; and,

FIG. 3 is a side elevational view of the tire as shown in FIG. 1, the opposite side elevational view being identical thereto.
